UNITED STATES PATENT OFFICE.

ROGER REYMOND, OF BRONX, NEW YORK, ASSIGNOR TO CURVE-LITE CORPORATION, OF NEW YORK, N. Y., A CORPORATION OF NEW YORK.

DIRECTIONAL AUTOMOBILE HEADLIGHT.

Application filed August 20, 1924. Serial No. 733,068.

This invention relates to automobile headlights of the character described and claimed in my copending application, Serial No. 715,795, filed May 26, 1924, wherein I disclosed a headlight having a movable reflector controlled by the action of centrifugal force, whereby the movement of a car in changing direction was instrumental in automatically shifting the reflector to light the path of the car. In the said prior invention, the whole reflector was bodily movable under the action of centrifugal force, as specified, and because of the relatively wide angle through which the reflector was adapted to move, a special form of lamp housing was desirable in order that all of the rays of the lamp might be emitted from the housing without blanketing.

The object of the present invention is to improve upon the former construction more particularly by permitting the use of the conventional form of lamp housing commonly employed on automobiles so that the use of a special housing is not necessary. The lamp of the present invention, in contradistinction to the former one, embodies two reflectors, one of which is, to all intents and purposes, substantially identical with the well known conventional reflector, being mounted in stationary position within the housing in the usual manner. The lamp is positioned in cooperative relation to this stationary reflector but between the lamp and said reflector is positioned a supplementary reflector of smaller size than the other and mounted for rotation on a vertical axis which includes the lamp. The movement of this latter reflector is controlled by centrifugal force and is capable of movement through a wide angle without blanketing any of the beam.

An important feature of the present construction resides in the fact that the invention may be applied to a conventional lamp in a simple and economical manner and a further important consideration resides in the fact that while the greater portion of the light from the bulb is directed into the path of the car, the remainder of the light from said source is directed substantially straight ahead of the car at all times. This is an advantage especially on country roads since the major beam from the movable reflector lights the path of the car while the second-

ary beam from the fixed reflector gives a lighter but less brilliant zone of vision, so that in the event of emergency the driver is better able to act.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a central vertical section through a headlight embodying the present invention; and,

Figure 2 is a horizontal section on the line 2—2 of Figure 1.

Referring to the drawings, 1 designates a lamp housing which, in practice, may be of the conventional form now in vogue. With this casing is associated the usual fixed reflector 2 and lens 3 held in place by a split ring 4 as is common. The housing is provided with a supporting stem 5.

The foregoing parts are well known and are in common use. In associating the present invention with a lamp housing of this character, I mount within the stem 5 a bulb supporting standard 6 adapted to project through an opening 7 formed in the fixed reflector and to the upper end of this standard attach a socket 8 to receive the bulb 9. Current is supplied to the bulb through a wire 10 which passes through the hollow standard 6 to the socket 8.

The standard 6 has a portion 10 of reduced diameter and upon this reduced portion a collar or carrier 11 is mounted for free rotation. The carrier is provided with an upstanding arm or bracket 12 and this bracket carries a reflector 14 which is positioned within the reflector 2 and back of the bulb 9. The reflector 14 is considerably smaller than the reflector 2, as will be seen from Figure 1 of the drawings, but is so positioned with respect to the source of light that the greater portion of the light from such source is received by and deflected from the reflector 14.

Pivoted to the carrier 11 is an arm 15, which extends rearwardly and carries thereon a roller 16 adapted for cooperation with

a stabilizer 17. The stabilizer is rigidly attached to the housing as at 18 and is curved longitudinally on a radius equal to the distance at which it is placed from the axis of the standard 6. The stabilizer is moreover provided with a longitudinal slot 19 and in this slot the wheel or roller 16 is adapted to travel. The slot is lowest at its center and slopes upwardly toward its ends and the roller is normally maintained at the base of the inclines and in midway position by means of a weight 20 secured to the end of the arm 15 beyond the roller 16.

Through the utilization of the weight 20, the roller is normally maintained midway of the slot 19 and in such position that the light impinging the reflector 14 is directed straight ahead. If, however, the car with which the headlight is associated changes direction, centrifugal force will act upon the weight 20 to carry it in a lateral direction after the manner fully described and claimed in my said copending case, wherein the stabilizer, as well as the weight 20, wheel 16 and arm 15 function in the identical manner as herein shown.

In order however to augment the action of centrifugal force, an additional weight 21 is attached to the carrier. When the car changes direction, centrifugal force will act in the manner described to rotate the carrier and, with it, the reflector 14, so that a beam of light is reflected from the reflector into the path of the car. This operation is graphically shown in Figure 2 wherein the movement of the car to the right effects shifting of the movable reflector 14 into the position shown in dot and dash lines while the movement of the car to the left results in movement of the moving reflector into the dotted line position, the normal position being shown in full lines. The angular deflection is manifestly controlled by the degree of curvature of the road which the car is traversing, and it is found in practice that the major beam from the reflector 14 will illuminate the true path of the car in negotiating a turn.

Such light as is not reflected by the moving reflector 14 will be reflected by the stationary reflector 2 and this secondary beam will be projected directly in front of the car. It is found in practice that the cooperation of these two beams is of great assistance in night driving particularly on country roads as the driver can not only see directly in the path of the car, but also has a broader range of illuminated vision which is very helpful in the event of an emergency.

Aside from the advantages of illumination as described, the present invention embodies marked features of advantage in construction, since the invention may be associated with conventional headlight construction thereby obviating the necessity of special

headlight construction with reference more particularly to the housing, stationary reflector, lens, etc.

While the invention has been particularly described in conjunction with a headlight, I am also aware that it may be employed in taillight construction.

The foregoing detailed description sets forth the invention in its preferred form, but it is to be understood as fully commensurate with the appended claims.

Having thus fully described the invention, what I claim as new and desire to secure by Letters Patent is:

1. A directional headlight for automobiles embodying a housing, a fixed reflector and a lens associated with the housing, a source of light positioned between the fixed reflector and the lens, a movable reflector of smaller diameter than the fixed reflector positioned between the source of light and fixed reflector and mounted for rotation coaxially with the source of light, said movable reflector being weighted off center of its axis of rotation, whereby it is operable by centrifugal force to oscillate in accordance with changes in direction of movement of the car with which the headlight is associated, and cam means for opposing the action of centrifugal force and normally maintaining the moving reflector in a position to direct a beam of light straight ahead.

2. A directional headlight for automobiles embodying a housing, a fixed reflector and a lens associated with the housing, a source of light positioned between the fixed reflector and the lens, a movable reflector of smaller diameter than the fixed reflector positioned between the source of light and fixed reflector and mounted for rotation coaxially with the source of light, an arm pivotally associated with the moving reflector and extending radially of its axis of rotation, an anti friction member associated with said arm, a cam cooperating with the anti friction member and a weight attached to the arm for rendering said arm responsive to centrifugal force, said cam being shaped to maintain the moving reflector in a position to direct a beam of light straight ahead and inclined to oppose the action of centrifugal force by the force of gravity whereby the resultant of these forces determines the position of the moving reflector when the direction of bodily movement of the headlight is changing.

3. A directional headlight for automobiles embodying a housing, a fixed reflector and a lens associated therewith, a vertically disposed standard adapted to support a bulb between the fixed reflector and lens, a carrier mounted to rotate on said standard, a moving reflector supported by the carrier and positioned between the bulb and the fixed reflector, said moving reflector being of less

diameter than the fixed reflector, a weight associated with the carrier off center to render the carrier responsive to the action of centrifugal force when the bodily movement of the lamp deviates from a rectilinear movement, and means for maintaining the moving reflector in a position to reflect a

beam of light straight ahead so long as the bodily movement of the headlight is a rectilinear movement.

10

In testimony whereof I have signed the foregoing specification.

ROGER REYMOND.
